UNITED STATES PATENT OFFICE.

GEORGE J. JOYNER, OF NEW YORK, N. Y.

MAIL-CASING AND DESPATCHING DEVICE.

1,097,329.

Specification of Letters Patent. Patented May 19, 1914.

Application filed January 18, 1913. Serial No. 742,796.

To all whom it may concern:

Be it known that I, GEORGE J. JOYNER, a citizen of the United States, residing at New York, in the county of New York and State 5 of New York, have invented new and useful Improvements in Mail-Casings and Despatching Devices, of which the following is a specification.

This invention relates to certain new and 10 useful improvements in mail casings and despatching devices and relates more particularly to improved means for holding the bags distended during the time of placing mail therein, and for tying up the bags after 15 filling thereof.

The object of the invention is to provide 20 simple, economical and practical means for holding the bags or cases open, which means can be easily and quickly applied to and removed from the bags, and further to provide casings which may be easily and quickly removed and replaced and tied up after filling.

In the drawings: Figure 1 is a fragmentary perspective view of a case showing bags 25 equipped with the present invention in the pigeon-holes of the case; Fig. 2 is a detached perspective view of one of the expanders; Fig. 3 is a similar view of one of the bags; 30 and Fig. 4 is a view similar to Fig. 3 showing the bottom of the bag.

The expander is used to hold the sack or bag in open or expanded position so as to enable the mail to be easily and conveniently placed within the sack or bag, and prior to the bag being closed or fastened after same has been filled with mail, the expander is removed, and for purpose of convenience of storage the expander may be placed in a pigeon hole as shown in Fig. 1 at the lower right hand pigeon-hole and the filled and closed bag or sack may also be then placed in the expander shown in said lower right hand pigeon-hole for convenience in storage until the closed bag is to be shipped.

The case 1 has the usual pigeon-holes 2, in which the mail bags or casings 3 are placed. The bags 3 each have a strap 4 attached to 50 their rear ends and have a loop 5 secured to their bottoms, the loop receiving the strap as shown. Each strap carries a label holder 6.

The expander is formed of a section of sheet metal which is bent into U-shape to form two opposite sides 7, 7, and a bottom 55 8 that connects the sides. The front end of the bottom 8 is formed with a downwardly bent lip 9 which engages the shelves of the case and also provides a finger grip, the lip having a label or the like placed thereon to 60 indicate different post-offices.

In operation, the expander is slid into the sack and the sack as shown in Fig. 1, is then placed in one of the pigeon-holes of the case. Mail matter is then placed in the 65 sacks and when the latter are ready for removal, the clerk removes the sack by engaging the end of the strap and the lip 9, whereupon the mouth of the sack is closed by drawing the strap ends thereacross, and 70 fastening said ends by the buckle 10.

From the above it will be seen that a great deal of time is saved in closing the bags, and tying thereof is eliminated, and bundle breaking or mixing in transit is 75 guarded against.

What is claimed is:

1. In combination with a mail bag, an expander therefor consisting of a U-shaped member formed of a section of sheet metal, 80 said member being insertible in the bag and having the free upper edges of the sides thereof for engagement with the top side of the bag, when the latter is in normal position in a pigeon-hole, the base of the member being provided with a lip that extends outwardly from the open end of the bag and downwardly therefrom and adapted to receive a label or the like.

2. An expander for mail bags consisting 90 of a U-shaped member formed of a section of sheet metal, the base of the member having an outwardly projecting lip to act as a finger grip to enable removal of the member from a mail bag and to also enable a label to 95 be placed thereon.

In testimony whereof I have hereunto set my hand in presence of two subscribing witnesses.

GEORGE J. JOYNER.

Witnesses:
